ROLLER SKATE

Knut O. G. Wetterstrand, Madison, N. J.

Application May 29, 1935, Serial No. 24,002

11 Claims. (Cl. 36—2.5)

This invention relates to new and useful improvements in roller skates and has for its main object the provision of a combined shoe with rollers affixed thereto, which may be moved into an inoperative position wherein the shoe may be of service and worn in the usual manner.

Another object is to provide a shoe which is equipped with rollers that may be normally enclosed in a recess in the heel and which may be moved into locations to provide the shoe with roller skating means.

Other objects and advantages of the invention will be apparent from the specification and accompanying drawings which show the preferred embodiment of the invention and wherein similar reference numerals indicate similar parts and wherein,

In the drawings:

Fig. 1 shows a front elevation of the shoe with rollers in operative position.

Fig. 2 shows a plan view of the bottom of the shoe with the rollers in operative position.

Fig. 3 shows a plan view of the shoe with rollers in inoperative position.

Fig. 4 is a section taken on line 4—4 of Fig. 2.

Fig. 5 is a section taken on line 5—5 of Fig. 3.

Fig. 6 is a section taken on line 6—6 of Fig. 4.

Fig. 7 shows a modification wherein runners are substituted for the rollers.

Fig. 8 is a section taken on line 8—8 of Fig. 7.

Fig. 9 is a detail view of a modified form of the lower support.

Fig. 10 is a plan view of a heel with a covering provided.

Fig. 11 is a section taken on line 11—11 of Fig. 10.

Referring to Figs. 1 and 2, a shoe 12 of any suitable, well-known form and style may be provided and the sole of the shoe 13 may have fixed and embedded therein a metallic plate 14 on

which will be affixed guide members 15 cooperating with a key-shaped member 16 (Fig. 6) so as to form a grooved track or guideway in which the members may be freely slid back and forth along the sole of the shoe. Securely fixed to the member 16 is a bracket 17 which supports a roller 18. This roller may be of any suitable material but in the preferred embodiment a molded material is shown which is molded into a tubular bearing member

19 having its ends formed over to form a ball race for the balls 20. Shaft 21 is journaled in the bracket 17 and is provided with an enlarged head 22 at one end and a threaded portion at the other for receiving screw 23. Collars 24 are provided

55 on this shaft to form the ball race in cooperation

with the formed over portion of the tubular bearing member 19. The bracket 17 is provided with two threaded apertures 25 into which are screwed wing bolts 26. These wing bolts may be screwed up to abut the guideway 15 and clamp the roller 5 into position to prevent its sliding. The previous description is that of the forward roller of the shoe. The rear roller is mounted in an identical manner on a bracket 27 which is hinged at 28 to the heel. The bracket 27 has an upwardly extending projection 28a integral therewith which cooperates with the back of the heel. The heel is reinforced by a metallic shell 29 which surrounds the heel and is provided with an insert 30 which is threaded to receive wing bolt 31 so that when 15 the roller is in the position in Fig. 7, the wing-bolt 31 is screwed into the insert 30 to hold the rear roller firmly in position.

The heel of the shoe is provided with metallic side walls 32 for strength and rigidity and is provided with a recess by being hollowed out with the exception of the rear section which has a somewhat thicker wall 33 of leather or other suitable material. A metallic annular ledge 34 is provided and supporting braces 35 extend from this lower 20 ledge to the heel for reinforcing the same. The guideway 15 extends along the sole and into the opening of the heel, there being an opening at the forward edge of the heel. When it is desired to place the rollers in inoperative position so that 30 the shoe may be worn in normal use without the rollers, the wing bolts 26 and 31 are loosened.

The rear roller is swung clockwise about its pivot 28 into the hollowed-out portion of the heel, and the forward roller is slid rearwardly along 35 the guideway and into the heel and clamped into position, thus locking the rear roller in the recess of the heel as shown in Fig. 5. A grooved cover 36 may be provided which may be slid into the bottom of the heel to provide a complete enclosure 40 for the rollers when in inoperative position.

Fig. 7 shows a modification in which a runner has replaced the rollers. The rollers may be removed by unscrewing the screw 23 and withdrawing the shaft 21. With the brackets 17 and 27 45 then located in their operative position, a runner 39 riveted to a tubular structure 40 and mounted by suitable methods to a supporting bearing 41 (Fig. 8) may be fastened to the brackets by means of wing bolts 42 cooperating with threaded holes 50 in the supporting structure 41. These supporting structures would be affixed and located on the tubular members 40 to correspond with the positions of the brackets 17 and 27.

In event skates of this type are used, the run- 55

ners may be removed, when their use is terminated, by unscrewing the wing bolts 42 to remove the runners and then move the brackets 17 and 27 into the heel as previously described in connection with Fig. 5.

Fig. 9 shows a modified form of the supporting brackets 17 and 27 for rendering the exchange of rollers and runners easier. In this modification a portion of the bracket is cut away as at 45 10 and a portion 46 is countersunk to engage a conical formed end of the wing bolt 42 as shown in Fig. 8 at 41. The engagement of this countersunk portion with the conical portion would satisfactorily prevent disengagement of the runner or 15 roller when clamped firmly for use.

The rollers 18 are formed in the shape of a truncated ellipsoid having their longitudinal dimension greater than their diametrical dimension. This permits the shoe or foot to be rocked 20 transversely to the direction of rotation of the roller to facilitate fancy figure skating and turning. The small diameter of the wheel and its extreme width creates less strain on the ankle and makes the skates less tiring to novices and 25 children.

In the use of the roller skates, for example, a child may skate to school and upon arrival he may move the rollers into the heel portion as shown in Figs. 5 and 3 and as previously described, and proceed to his classroom wearing the same shoes without the use of the rollers. Also in factories where messengers use roller skates while delivering mail and orders from a central dispatch office, while the messengers are working 30 in the office the rollers may be kept concealed in the heel and moved into their operative position when the messenger leaves the office to make his rounds in the shop.

While the fundamental novel features of the 40 invention have been described and pointed out, it will be understood that various omissions and substitutions and changes in the form and details of the device illustrated and in its operation may be made by those skilled in the art without departing from the spirit of the invention. I intend to be limited therefore only as indicated by the 45 scope of the following claims:

1. A shoe having a sole and a heel with a recess, guiding means in the sole extending longitudinally of the shoe and into the recess and a roller supporting bracket slidably mounted in said guiding means.

2. A shoe having a heel with a recess, and a roller supporting bracket pivoted to said heel, a roller mounted on said bracket, and means for swinging said roller and bracket entirely within said recess.

3. A shoe having a heel with a recess, front and rear rollers positioned within said heel and means for moving said rollers externally of said heel to fixed locations at the front and rear of said shoe respectively.

4. A combination shoe and roller skate, including a heel having a recess, a roller bracket pivotally mounted on said heel and normally lying within said recess, whereby said roller may be swung out of said recess into operative position. 5

5. A combination shoe and roller skate, including a heel having a recess, a roller bracket pivotally mounted on said heel and normally lying within said recess, whereby said roller may be swung out of said recess into operative position, and means for locking said roller into operative position. 10

6. A combination shoe and roller skate including a heel having a recess, a sole having a guideway extending substantially the length of the 15 sole, a roller supporting bracket slidably mounted in said guideway and normally positioned within said recess, said bracket being slidable along said guideway and into operable position.

7. A combination shoe and roller skate including a heel having a recess, a sole having a guideway extending substantially the length of the sole, a roller supporting bracket slidably mounted in said guideway and normally positioned within 20 said recess, said bracket being slidable along said guideway and into operable position, and means 25 for locking said bracket in said roller in operative position.

8. A combination shoe and roller skate including a heel having a recess, a sole having a guideway extending substantially the length of said sole, a forward roller and a rear roller normally positioned within said recess, said forward roller being slidable along said guideway into operative position and said rear roller pivotable on the 30 heel, into operable position.

9. A shoe having a sole and a heel with a recess, a pair of brackets adjustably mounted on said shoe adapted to have either rollers or runners mounted thereon, said brackets being movable into said recess without being removed from the shoe. 40

10. A shoe having a recess, a skating roller movable into the recess, a carrier for the roller and means movably mounting the carrier on the 45 shoe for movement into a position in which the roller is concealed in said recess and into an alternative position external of the recess in which the roller is in skating position outside the recess. 50

11. In a combined shoe and roller skate, a single recess in one portion of said shoe, a plurality of rollers with carriers for each roller movably mounted on said shoe and a plurality of carriers for supporting said rollers, said carriers being 55 movably mounted to said shoe whereby said carriers and rollers may be moved to fit within said single recess.

KNUT O. G. WETTERSTRAND. 60
